J. DANIELE,
DOOR STOP.
APPLICATION FILED NOV. 13, 1919.

1,354,469.

Patented Oct. 5, 1920.

Inventor,

Joseph Daniele;

By

A. B. Leapham,
Attorney.

UNITED STATES PATENT OFFICE.

JOSEPH DANIELE, OF NEEDHAM, MASSACHUSETTS.

DOOR-STOP.

1,354,469.

Specification of Letters Patent.

Patented Oct. 5, 1920.

Application filed November 13, 1919. Serial No. 337,759.

To all whom it may concern:

Be it known that I, JOSEPH DANIELE, a citizen of the United States, and a resident of the town of Needham, in the county of Norfolk and Commonwealth of Massachusetts, have invented certain new and useful Improvements in Door-Stops, of which the following is a full, clear, and exact specification.

- 10 It is customary to attach to the base board of a room or to the floor thereof, a rubber-protected knob for receiving the impact of a door when swung wide open. Ordinarily these door stops are provided with a 15 projecting wood-screw which can be screwed into the base-board or the floor by forcibly turning the stop itself. These screws soon work loose, however, so that the door-stops fail to remain in place, and finally will come 20 out at the smallest provocation.

The object of this invention is the effecting of means whereby the door-stops will be retained in place with perfect security and firmness, and can be removed and replaced 25 at will without loosening its hold.

To this end, I provide a metal disk adapted to be attached to the base-board or to the floor, and having a central hole tapped to receive a bolt; the door-stop being given an 30 axially disposed bolt adapted to screw into said hole.

In the drawings forming part of this specification, Figure 1 is a central longitudinal section of a door-stop embodying my 35 improvements, the same being of the kind customarily attached to a base-board. Fig. 2 is a similar section of a door stop of the kind usually attached to the floor, but here 40 illustrated as attached to a wall or base board. Fig. 3 is a face view of the metal attaching disk. Fig. 4 is a section on the line 4—4 in Fig. 1.

In the drawings, the reference numeral 1 designates the knob or door stop having 45 a stove-bolt 2 axially disposed therein; in Fig. 1, the knob being shown as provided with an axially arranged rubber plug 3, while in Fig. 2 the knob is illustrated as provided with a circumferentially disposed rubber ring 4.

For fastening the bolt 2 firmly in the knob 1 and 1^a, the inner end of the knob is chambered, as at 5, for the reception of a nut 6. This nut being firmly turned against the 55 inner surface of the chamber or recess 5, while the bolt head 7 rests against the outer end of the knob 1^a, as in Fig. 2, or

against the inner end of an elongated recess 9, as in Fig. 1, the bolt is solidly clamped in place.

The attaching disk 10 has an internally threaded hole 11, and preferably three screw holes 12 suitably countersunk. This disk is to be fastened to a base board 13 or to the floor at the desired place by means of wood 60 screws 14 having their heads flush with the outer surface of the disk. A hole 15 is also bored through the hole 11 for a suitable distance into the base-board or floor to receive the end of the bolt 2.

The bolt 2 is then introduced into the threaded hole 11 and turned by the forcible rotation of the knob until the inner end of the latter is solidly against the disk, the bolt-threads cutting their way into the hole 70 15. The bolt end is illustrated in the drawings as reaching for a considerable distance into the base-board. While this aids in giving rigidity to the knob, through the grip of the wood on the bolt, it is not actually necessary, since the three wood screws bind the disk to the base-board with all necessary firmness, and the bolt confines the knob rigidly to the disk.

Although the disk 10 is shown as attached 85 to the surface of the base board 13, it can as well be set therein, a bit of proper diameter being used for cutting into the wood.

Thus constructed, the door stop is permanently held firmly and immovably, and yet 90 it can easily be removed at any time for repainting or cleaning the wood work, and be returned to be as firmly held as before.

What I claim is:

A door stop comprising a knob having a 95 circular base, a metal disk equal thereto in diameter, having a plurality of screw holes near the periphery of said disk suitably countersunk to receive the heads of the screws to be used therein, said disk having 100 a central hole threaded for the reception of a stove bolt, and a stove bolt passed axially through the knob into engagement with said central hole, whereby said disk can be screwed to a floor or mop-board by 105 wood-screws introduced through said peripheral holes, and the knob can be easily removed therefrom and replaced thereon without loosening its hold thereon.

In testimony that I claim the foregoing 110 invention, I have hereunto set my hand this 1st day of November, 1919.

JOSEPH DANIELE.
